FOLDING BATH TUB

Walker P. Mayo and Reba H. Mayo,
Prestonsburg, Ky.

Application July 25, 1947, Serial No. 763,690

8 Claims. (Cl. 4—176)

1

This invention relates to new and useful improvements in folding bath tubs.

One object of the invention is to provide an improved folding bath tub particularly adapted for use by invalids and convalescents, whereby they may conveniently bathe themselves with a minimum effort or largely assist in so doing.

Another object of the invention is to provide an improved tub, of the character described, which includes an elevated seat section, simulating a deep chair, with a foot section hinged thereto and adapted to be lowered to the floor, whereby an invalid or convalescent may sit in the seat section and, after positioning his legs and feet in the foot section, may raise the latter into horizontal alinement with said seat section, thus permitting water to be deposited in the tub and later drained therefrom.

A further object of the invention is to provide an improved folding tub of the character described, wherein a pivoted prop is provided for its hinged foot section which is accessible to the person sitting in its seat section, the tub having means operable by such person for raising and lowering the foot section.

Still another object of the invention is to provide an improved folding tub wherein the bottoms of its sections are connected by a transverse hinge and portions of the section bottoms and sides have co-acting packing means with inter-engaging elements arranged to separate when the foot section is lowered and to engage and form a water-tight seal when said foot section is elevated.

A particular object of the invention is to provide an improved tub, of the character described, which is of such construction that semi-invalids or ambulatory patients may place themselves in the tub and raise the foot section, preparatory to bathing themselves, for the reception of water.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a perspective view of a folding bath tub, constructed in accordance with the invention, and illustrating the lowered position of the foot section in dotted lines,

Fig. 2 is a plan view of the tub,

Fig. 3 is an enlarged, transverse, sectional view of the seal and hinged joint,

2

Fig. 4 is a view, partly in perspective and partly in section, of the drum and cable actuating means, and

Fig. 5 is a perspective view of one of the brace pockets.

In the drawing, the numeral 10 designates a seat section having a foot section 11 hinged thereto, the two sections when alined forming a complete bath tub. The exact construction of the sections is variable. The seat section has the general structure of the head section of an ordinary metal or porcelain bath tub; however, it is preferable to provide along each side of this section, moderately curved arm flanges 12 which are merged into a head roll 13, at the back of the section. The seat section is secured on the top of a stand or upright support 14, which includes legs 15 connected by cross braces 16 near their lower ends. Rollers or casters 17 are journaled in caster brackets 18 secured in the lower ends of the legs, whereby the stand and tub are made portable. A stop 19 is pivoted to the lower end of one of the legs and may be swung downwardly into engagement with the floor, when it is desired to hold the stand against rolling.

A hanger strip 20 is secured across the bottom of the section 10 at its front edge, said strip being offset transversely so that its front portion (Fig. 3) is spaced from the bottom of the section. A similar hanger strip 21 is secured to the adjacent edge portion of the bottom of the foot section 11. The leaves of a transverse hinge 22 are secured to the offset portions of the strips by welding or other suitable means. The strips and the hinge are so positioned that when the foot section is swung to a horizontal position, the edge portions of the sections are spaced apart, as shown by the numerals 23 and 24.

It is obvious that a water-tight seal must be provided between the sections, when they are alined, in order to hold water. An elongate, elastic female sealing member 25 is secured to the edge portion 23 and receives a portion of an elastic complementary sealing member 26 when the members are alined. The female member 25 extends across the bottom and up each side of the seat section 10 and has a longitudinal groove or recess 27 which snugly receives the edge portion 23, whereby the sealing member is supported in place. Along its front edge, the member has a longitudinal socket 28. The member 26 has a recess 29 for receiving the edge portion 24 of the foot section and is formed along its front or outer edge, with an elongate bead

30 which engages tightly in the socket 28 when said foot section is raised to a horizontal position.

On one side of the seat section 10, a stub shaft 31 is suitably mounted so as to extend outwardly. A drum 32 is rotatably confined on the shaft and has one end of a cable 33 wound on its hub (Fig. 4). This cable passes over a pulley 34 on the side of the seat section and thence over a pulley 35 on the side of the foot section 11 (Fig. 1). The outer end of the cable is attached to the side of the foot section near its outer end, the pulleys being at higher elevations than the drum and the point of attachment of the cable.

For rotating the drum, a handle 36 is eccentrically mounted thereon. A ratchet wheel 37 is secured on the hub of the drum lever 38, pivoted adjacent the wheel, has a dog 39 on its lower end engaging the teeth of said wheel. A coiled spring 40 has one end attached to the lever 38, upwardly of the pivot point thereof, and its opposite end attached to the side of the seat section, whereby the dog 39 is held in yieldable engagement with the ratchet wheel 37. The upper free end of the lever projects under and beyond the front end of one of the arm flanges 12, whereby it may be grasped by the bather and the lever depressed for releasing the drum so that the foot section may be lowered. Suitable latches 41 may be provided at the upper ends of the joint between the sections for fastening said sections together.

For supporting the foot section 11 in a horizontal position, a prop 42 is provided. This prop is U-shaped and has its upper ends pivoted to the outer end of the section on each side thereof. Inclined braces 43 have their lower ends pivoted to the prop intermediate the ends of the latter. The upper ends of the braces engage in pockets 44 on each side of the foot section. The outer end 45 of the foot section is inclined upwardly and outwardly so that when said section is lowered, said end 45 will rest flat on the floor, as is shown in dotted lines in Fig. 1. A drain 46, having a suitable closure 47, is provided in the bottom of the seat section and a hose (not shown) may be connected to the drain for removing water from the tub. If desired, the braces 43 may be removably connected to the prop, such as by J-slots 48.

In using the bath tub, the foot section 11 is swung downwardly into engagement with the floor. The invalid or convalescent person may walk onto the flat end 45, turn around and sit in the seat section 10. Then, by grasping the handle 36 and rotating the drum 32 to wind the cable 33 on its hub, the foot section may be raised and aligned with the seat section 10, and then latched. Since the prop 42 is hinged to the foot section, it will swing from the position shown in dotted lines in Fig. 1 toward its full line position. The bather may reach down and swing the braces 43 upwardly and engage their ends in the pockets 44.

Someone may place water in the tub or faucets (not shown) may be conveniently located so that the user may push the tub under the faucets before entering it. After draining water from the tub, by way of the drain 46 and any suitable means (not shown), the bather can disconnect the latches 41, release the prop 42 and lower the

foot section by depressing the lever 38. The user merely rises and walks from the tub.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters

10. Patent is:

1. A folding bath tub including, a seat section, a foot section hinged to the seat section, packing means sealing the joint between the sections, a support maintaining the seat section at an elevation, and a movable support holding the sections aligned and movable to permit downward swing of the foot section.

2. A folding bath tub as set forth in claim 1, with actuating means on the seat section having 20 connections with the foot section for raising and lowering said foot section.

3. A folding bath tub as set forth in claim 1, wherein the foot section has an end inclined to rest substantially flat on the floor when the 25 section is swung downwardly.

4. A folding bath tub as set forth in claim 1, with a drum mounted on the seat section, a flexible connection wound on the drum and having one end attached to the foot section, and 30 retaining means on the drum.

5. A folding bath tub including, an elevated seat section, a foot section hinged to the seat section, a prop pivoted to the foot section, and braces hinged to the prop and engaging the seat 35 section.

6. A folding bath tub as set forth in claim 5, with a drum and cable connecting the sections for raising and lowering the foot section.

7. A folding bath tub including, a seat section, a foot section hinged to the seat section, an elastic female seal on the seat section, and 40 elastic male seal on the hinged end of the foot section engaging in the female seal for sealing the joint between the sections.

8. A folding bath tub including, a substantially horizontal seat section, an upright stand upon which the seat section is mounted, a foot section hinged at its bottom to the bottom of the seat section, an elastic seal at the joint 45 between the sections, a prop pivoted at its upper end to the foot section, and drum and cable means carried by the seat section and attached to the foot section for raising and lowering the foot section.
